PADLOCK

Filed Aug. 7, 1930

UNITED STATES PATENT OFFICE

SAMUEL R. FRAIM, OF LANCASTER, PENNSYLVANIA

PADLOCK

Application filed August 7, 1930. Serial No. 473,562.

One purpose of my invention is to facilitate padlock manufacture by formation of the padlock body from a solid block and separate assembly of the complete locking mechanism for inclusion within it.

A further purpose is to provide a new and desirable lock assembly for easy insertion in a straight cylindrical bore of a padlock body.

10 A further purpose is to concentrically surround a key plug with an outer casing, to transversely guide a bolt in the end of the casing and to fit the assembled unit inside a straight bore in the body of a padlock.

15 A further purpose is to preliminarily retain a cylindrical casing about a disc tumbler plug for the double purpose of holding them together for assemblage and of limiting the angular movement of the disc tumbler plug.

20 A further purpose is to provide an arcuate pin and slot connection between a barrel or key plug and a casing, adapted to be mounted as a lock-operating unit in the body of a padlock.

25 A further purpose is to adapt a disc tumbler locking plug to padlock use.

A further purpose is to additionally carry a locking bolt in a plug lock for insertion within an upwardly directed bottom bore of

30 the padlock body.

A further purpose is to operate a transversely-spring-pressed bolt for the short arm or toe of the shackle of a padlock in the upper end of a light casing surrounding a key plug

35 having operative connection with the bolt and angular lock and key connection with the casing, preferably including tumblers of the disc type.

40 A further purpose is to provide a novel form of padlock for easy manufacture and assembly and including a body having a straight bore and an insert unit therein comprising a transverse bolt, an outer casing mounting and guiding the bolt and a disc

45 tumbler key plug inside the casing adapted to be turned with respect to the casing when a suitable key has been inserted in the plug.

Further purposes will appear in the specification and in the claims.

50 I have elected to illustrate one main form

only of the many forms of my invention, showing however a minor modification and selecting a main form that is practical and efficient in operation and which well illustrates the principles involved.

Figure 1 is a side elevation of a padlock embodying a desirable form of my invention, the shackle being shown closed in full line and open in dot-and-dash line.

Figure 2 is a side elevation of Figure 1.

Figure 3 is a bottom plan view of Figure 1.

Figure 4 is a vertical section taken upon the line 4-4 of Figure 2, the shackle and plug being not sectioned and a key inserted in the barrel being shown in dot-and-dash.

Figure 5 is a vertical section taken upon the line 5-5 of Figure 4 without sectioning the barrel.

Figure 6 is a horizontal section taken upon the line 6-6 of Figure 4.

Figure 7 is a horizontal section taken upon the line 7-7 of Figure 4.

Figure 8 is a horizontal section taken upon the line 8-8 of Figure 4.

Figures 9 and 9a are upper and lower perspective views of a detail, being a bolt element of an insert unit.

Figure 10 is a perspective view of a detail of the insert unit, the sleeve or casing element thereof.

Figure 11 is a perspective view showing another detail of an insert unit, a key plug for assembly with the casing of Figure 10.

Figure 12 is a perspective view showing the structure of Figures 10 and 11 assembled together, the casing being partly broken away to more fully disclose an operating cam on the upper end of the key plug.

Figure 13 is an assembly view of the insert lock member, including the bolt of Figure 9, the casing of Figure 10 and the key plug of Figure 11.

Figure 14 is a top plan view of Figure 12.

Figure 15 is a vertical section corresponding generally to Figure 5 but modified with respect to a minor detail.

Like numerals refer to like parts in all figures.

Describing in illustration and not in limitation and referring to the drawing:—

Referring to the drawing, the lock comprises a body 20, shackle 21 and lock insert 22.

The body 20 preferably comprises a short length cut from a continuous solid bar, the section being bored in a longitudinal direction from one end (the top of the body) at 23 and 24 to receive the long and short ends of the shackle 21 and bored upwardly from 10 the other end (the bottom) at 25 to receive the lock insert 22, the upward bore 25 for the insert preferably cutting into the downward bore 24 for the short end of the shackle in order to permit a spring bolt 26 at the upper 15 end of the insert to latch into an inwardly directed notch 27 at the toe of the shackle.

The longer arm of the shackle is circumferentially grooved near its lower end at 28 and one side of the arm is flattened at 29 upwardly from the bottom of the groove for a distance equal to the desired upward opening stroke of the shackle, a pin 30 through the body having a portion of its thickness extending across the flat side.

25 When the lock is opened the shackle is free to move upwardly until stopped by the head at the lower side of the groove 28 engaging the pin 30, after which the open shackle is free to rotate upon its long arm, the groove 30 28 alining with the pin 30, and the pin and groove connection preventing downward movement of the shackle in the usual way except when the short arm of the shackle is in proper alinement with the hole 24 of the 35 body.

The insert unit 22 includes an inner plug (barrel) 31 (Figure 11) carrying disc tumblers, an outer shell or sleeve 32 (Figure 10) and the bolt 26 (Figures 9 and 9a) mounted 40 on the upper end of the sleeve and presenting a downwardly extending dog 33 to an operating cam 34 on the top of the barrel 31.

The intermediate portion of the barrel includes an assembly of tumbler discs 35 spring-45 pressed to normally project outwardly from one side of the plug and adapted to be moved inwardly by the insertion of a suitable key to lie even with the circumference of the plug, or at least, not to project beyond this circumference.

The barrel is provided with a head or flange 36 at its lower end adapted to circumferentially fit and close the entrance into the bore 25 in the body.

55 The sleeve 32 is cut away at the locking ends of the tumbler discs to permit the ends of these discs to normally project outwardly across the thickness of the shell to lock the barrel from turning with respect to the sleeve if the key is not inserted in the barrel.

While obviously I may provide the ends of the tumbler discs with individual arcuate keyhole slots in the shell I usually prefer to provide a single keyway slot 37 cut longitudinally upwardly from the lower end of the

shell in registry with the locking ends of the disc tumbler members 35, and may also provide a corresponding slot 38 upwardly from the lower end of the shell at the opposite ends of the tumbler discs.

Normally after assembly of the sleeve and plug the locking ends of the tumblers 35 project into the slot 37 to prevent angular movement of the plug or barrel with respect to the sleeve.

75 Insertion of a key 39 moves the tumbler discs longitudinally back in the usual way, the rearward ends of one or more of the tumblers with usual length of tumblers momentarily moving out beyond the line of the barrel into the slot 38 on the other side of the sleeve, this slot functioning merely to permit the inward movement of the disc members during the insertion of the key and being optionally dispensed with if the rearward ends of the tumblers are made sufficiently short to avoid the need for their projection beyond the outer circumference of the plug during key insertion.

80 The barrel in so far as it includes the transversely mounted tumblers 35, adapted to be retracted against individual springs 40 by the insertion of the key at a keyhole 41, the key variably positioning surfaces 42 of the tumbler to register the tumblers in retracted 85 position, is of the prior art and well known.

85 The upper end of the shell or sleeve 32 includes a transverse guide 43 for the bolt 26, the guideway having desirably a suitable downward flare to prevent upward movement 100 of the correspondingly flared bolt in a direction longitudinal of the sleeve.

This however is also somewhat a matter of preference, the principal advantage being a holding of the bolt in the insert unit before 105 the insertion of the unit into the body of the lock, and making it unnecessary to secure any close sliding fit between the top 44 of the bore 25 and the top surface of the bolt 26.

I prefer to have the top of the bolt substantially against the surface 44 in order that any force due to any outward pull upon the shackle in a direction to open the lock will be supported by the body member at 44. However it must not rub against surface 44.

110 The bolt 26 is longitudinally recessed at 45 to receive one end of a spring 46, the other end of the spring engaging the body and pressing the bolt outwardly as best seen in Figure 4, to make latch engagement with the notch 115 on the short end or toe of the shackle when this end is inserted into the body.

Desirably the lower forward side of the bolt is upwardly recessed at 47 to shorten the requisite downward extension of the shackle 120 end and to lessen the downward overlap of this end with respect to the sleeve, the sleeve being shown cut away arcuately at 48 to receive the end of the shackle.

125 The sleeve is hollow upwardly from the

bottom to receive and fit the upper portion of the plug and is perforated longitudinally at 49 into the transverse guideway 43 to permit cooperating engagement and movement 5 of the downwardly directed dog 33 upon the bolt and the upwardly directed cam 34 on the upper end of the barrel.

I preferably form the barrel with respect to the cam and dog to limit the angular movement of the barrel with respect to the sleeve 10 to that needed to satisfactorily operate the lock.

As seen in Figure 12 I have made the cam of semi-circular section, encasing it except 15 for a diametral portion engaging the dog with the sleeve to limit the range of movement of the barrel.

It will be seen that I have provided a form of lock insert particularly well adapted to 20 use in the manufacture of padlocks having bodies comprising successive sections of a solid bar, bored on one side to receive the ends of the shackle and on the other to receive my insert, the insert including a light shell carrying a bolt at one end and a barrel inside the shell having suitable operative connection with the bolt and angularly locking with the shell.

I preferably make this insert as a unit, with 25 the constituent members keeping their assembled positions in the unit unless definitely withdrawn, and as illustrated in Figures 12 and 13 may desirably provide a slot 50 and pin 51 connection between the barrel and shell 30 as indicated which normally prevents longitudinal withdrawal of the barrel from the shell but permits angular movement of the barrel with respect to the shell to operate the bolt. It also acts as an aligning limit to 35 ensure registry of the tumbler extensions 35' with the slots 37, 38.

I may prevent removal of the shell from the body in a number of different ways, illustrating a suitable perforation 52 in the shell 45 adapted to receive a pin 53 through the body after the shell has been inserted.

Optionally I may provide sufficient resistance to angular movement between the shell and the body by making a light driving fit 50 between the shell and body.

In Figure 4 I illustrate the barrel prevented from longitudinal withdrawal from the body and therefore from the shell after the unit has been inserted by a pin 54 that extends 55 laterally into a groove 55 around the flange 36 of the body.

The pin and groove connection is sufficiently loose to permit angular movement of the plug and if the fit between the shell and body be sufficiently tight to prevent angular movement of the shell with respect to the body I may dispense with other fastening between the assembled units than the single pin 54.

65 If it be deemed preferable to make the

shell fit loosely into the body I may provide another or a different pin connection between the body and shell, a pin 53 (Figure 15) for example of the body suitably projecting through the shell to extend into an 70 arcuate groove 56 in a portion of the barrel suitably away from the tumbler disc 35, either at the upper end, as indicated in Figure 15 or at the lower end, as indicated in Figure 4, and with the pin extending either 75 tangentially to the groove as indicated in Figure 4 or directly into the groove as indicated in Figure 15. Extension of the edge 58 of cam 34 beyond the central axis of the disc projection 56 makes it engage with a 80 shoulder 59 upon the casing giving an additional means of checking rotation of the plug within the casing to insure registration of the tumbler extensions 35' with the groove 85 37. In the illustration in Figure 12 this is supplemental to the slot and pin connection between the sleeve and plug but may be used instead of it. Either or both insure freedom from frictional engagement of the tumbler extensions 35' with the side wall of the slot 90 at the same time that the key is in position for removal.

In view of my invention and disclosure variations and modifications to meet individual whim or particular need will doubtless 95 become evident to others skilled in the art, to obtain all or part of the benefits of my invention without copying the structure shown, and I, therefore, claim all such in so far as they fall within the reasonable spirit and 100 scope of my invention.

Having thus described my invention, what I claim as new and desire to secure by Letters Patent is:

1. A padlock including a shackle, a body 105 mounting the shackle at one end and having a straight cylindrical bore from the other end and an insert within the bore comprising a transverse bolt, an outer casing mounting and guiding the bolt and a disc tumbler key 110 plug inside the casing adapted to be turned with respect to the casing when a suitable key has been inserted in the plug.

2. A padlock body having openings for 115 the long and short shackle legs in one end and for a lock assembly in the other end, the short shackle opening communicating with the lock assembly opening, a shackle for the shackle opening and a lock assembly for the 120 assembly opening, the assembly comprising a disc tumbler plug, a casing about the plug, in use fixed within the body, slotted to permit locking engagement of the discs and carrying a transverse bolt guide and a 125 spring-pressed bolt transversely movable within the guide and controlled by the position of the plug, the opening at the said other end comprising a straight cylindrical bore, and the assembly circumferentially fit- 130

ting the bore and adapted for insertion as an assembled unit at the open end thereof.

3. A padlock body having openings for the long and short shackle legs in one end and for a lock assembly in the other end, the short shackle opening communicating with the lock assembly opening, a shackle for the shackle opening and a lock assembly for the assembly opening comprising a disc tumbler plug, a casing about the plug concentric with the plug, in use held against movement within the body, a transversely guided bolt carried by the casing and cam connections between the plug and bolt controlling the position of the bolt with turning movement of the plug, the opening at the said other end comprising a straight cylindrical bore, and the assembly circumferentially fitting the bore and adapted for insertion as an assembled unit at the open end thereof.

4. A padlock body having openings for the long and short shackle legs in one end and for a lock assembly in the other end, the short shackle opening communicating with the lock assembly opening, a shackle for the shackle opening and a lock assembly for the assembly opening comprising a disc tumbler plug, a casing about the plug concentric with the plug, extending beyond it and transversely slotted to form a bolt guide and a bolt in the guide, the opening at the said other end comprising a straight cylindrical bore, and the assembly circumferentially fitting the bore and adapted for insertion as an assembled unit at the open end thereof.

5. A padlock body having openings for long and short shackle legs in one end and for a lock assembly in the other end, the short shackle opening communicating with the lock assembly opening, a shackle for the shackle openings and a lock assembly for the assembly opening comprising a tumbler plug, a casing about the plug concentric with the plug, extending beyond it and transversely slotted to form a bolt guide, a bolt in the guide, and the assembly fitting the contour of the opening in the body and adapted for insertion as a unit into the body opening.
